UNITED STATES PATENT OFFICE

123,744

DESIGN FOR A DRESS

Christine Mazola, New York, N. Y.

Application September 25, 1940, Serial No. 95,365

Term of patent 3½ years

To all whom it may concern:

Be it known that I, Christine Mazola, a citizen of the United States and a resident of the city of New York, in the county of New York and State of New York, have invented a new, original, and ornamental Design for a Dress, of which the following is a specification, reference being had to the accompanying drawing, forming a part thereof.

Fig. 1 is a front view of a dress showing my new design.

Fig. 2 is a rear view of the dress shown in Fig. 1. The characteristic feature of my design resides in the combination on the specific dress disclosed of the beaded embroidery on the shoulder yokes and around the back of the collar in association with the matching beaded embroidery on the belt, as shown.

I claim:

The ornamental design for a dress, substantially as shown and described.

CHRISTINE MAZOLA.
